UNITED STATES PATENT OFFICE

2,282,214

METAL SPRAY GUN

Frans O. Albertson, Sioux City, Iowa, assignor to
 Albertson & Company, Inc., Sioux City, Iowa,
 a corporation of Iowa

Application July 6, 1937, Serial No. 152,104

7 Claims. (Cl. 91—12.2)

The present invention relates to metal spray guns, and is particularly concerned with improvements in metal spray guns of the type covered by my prior Patent No. 2,058,653, issued April 30, 1936, and my prior application, Serial No. 143,718, filed May 20, 1937, for Metal spray gun. The present application is a continuation-in-part of my prior application, Serial No. 143,718, filed May 20, 1937, for Metal spray gun.

One of the objects of the present invention is to provide an improved metal spray gun which will be kept at proper starting temperature by thermostatic control and which is adapted to give instant heat when the solder is inserted and melted in the metal well at the nose of the gun, and which is also adapted to boost the heating temperature as soon as the gun begins operating.

In a thermostatically controlled metal spray gun not having the features of the present invention, the nose of the gun cools off first, as soon as the operator starts melting solder. It takes some time before this cooling effect travels to the thermostat, and therefore the gun is apt to cool too quickly as soon as solder is applied to it.

Another object of the present invention is to apply an instant supply of additional heat to the gun as soon as the gun starts to melt solder, so that the gun will not get too cool and will be maintained at a proper temperature for melting solder.

Another object of the invention is to provide an improved metal spray gun adapted to be controlled by a thermostatic switch so as to prevent heat damage to the gun, and in which the thermostatic switch is so arranged that the gun temperature at which it is actuated is changed when the gun is actually being used and the air is turned on, so that the gun may be kept at one temperature when it is idle but ready, and at another predetermined but higher temperature when the gun is actually being used.

Another object of the present invention is the provision of a thermostatically controlled and air cooled spray gun of the class described, in which the air supply is used to cool the thermostat so as to cause an immediate closure of the thermostatic switch when the gun is put in actual operation, to give instant heat at that time and to raise the operating temperature a predetermined amount while the gun is in operation.

Other objects and advantages of the invention will be apparent from the following description and the accompanying drawing, in

which similar characters of reference indicate similar parts throughout the several views.

Referring to the single sheet of drawings,

Fig. 1 is a vertical sectional view, taken on a vertical plane passing through the axis of the air nozzle and the axis of a metal well, showing the details of construction of the gun;

Fig. 2 is a bottom plan view of the thermostatically operated control switch, taken on the plane of the line 2—2 of Fig. 1;

Fig. 3 is a fragmentary vertical sectional view of the thermostatic switch, taken on the plane of the line 3—3 of Fig. 2, looking in the direction of the arrows;

Fig. 4 is a vertical sectional view, taken on the plane of the line 4—4 of Fig. 2, looking in the direction of the arrows, showing further details of construction of the thermostatically operated switch.

Referring to the drawing, 10 indicates in its entirety the metal spray gun, which is provided with a handle 9 for the purpose of supporting the gun during its operation.

The gun proper preferably comprises a rear body portion 11 and a forward body portion 12, these body portions being separated from each other by a plurality of projecting lugs 13 carried by one or the other of said body portions to reduce the conduction of heat between the bodies to a minimum.

The body 11 preferably houses an air conduit 14, which may be connected by the usual fittings, and an air hose 15, to a supply of air under pressure. The conduit 14 is controlled by an air valve 16, which is spring pressed to closed position, but may be opened by means of a push rod 17 actuated by a trigger 18 carried by the handle 9. The air conduit 14 communicates with the air tube 19, which begins in the body 11 and extends through the body 12, terminating in an arcuate air nozzle 20.

The air tube 19 supports the porcelain body 21, which carries the helically coiled and wrapped electric heating element 22. The body 12 may be of substantially inverted trough shape, the open side being closed by the lower cover plate 23, secured in place by a plurality of screw bolts. The left end of the body 12 is provided with an upwardly extending nose formation 24, provided with a tapered bore 25, which forms a metal well.

The metal well 25 extends down to the bottom of the nose 24, where it terminates in a bronze metal nozzle 26, having a reduced nozzle opening which terminates within the arc of the

air nozzle opening 20. 21 indicates the stick of meltable metal of a composition described by my prior applications, which is thrust into the metal well 25 and melted by the heat of the body 12, the body 12 being heated by the electric heating element 22.

The body of the gun 10 is preferably supported in spaced relation to the handle 9 by means of a plurality of metal supporting posts 28, preferably four in number, and located at the four corners of the upper supporting body 29 of the handle. The supporting post 28 may be provided with a multiplicity of spacer rings 30 and heat radiating fin plates 31 carried by the posts, and a multiplicity of other rectangular plates 32 may be mounted on the same posts in spaced relation to each other for radiating heat which might be conducted to them from the upper hot body of the gun.

The major portion of the heat which is transferred to the posts 28, fins 31, and plates 32 is thus dissipated by radiation, due to the increased radiating area of the plates and fins.

The trigger 18 is pivotally mounted at 33 on the handle 9 by means of the bracket 34. The body 29 of the handle 9 supports a bracket plate 35, which in turn supports a second bracket plate 36, upon which the trigger 18 is mounted. The push rod 17 is slidably mounted in a multiplicity of aligned rectangular apertures in the plates 32, and its end rests upon a cross pin 37, which is carried by two rearwardly projecting flanges 38, forming a part of the trigger 18.

Each end of the cross pins 37 is grooved to receive the hooked end of a helical coil spring 39, each of which is provided with initial tension by having its lower end hooked to a part carried by the bracket 36. Thus the springs 39 urge the trigger 18 to the position of Fig. 1. When the trigger 18 is pulled, it pivots in a counterclockwise direction on the pivot 33, and moves the pin 37 upward, which moves the push rod 17 to engage the flange 16 and open the valve in the conduit 14.

The lower reduced end of the push rod 37 is also confined behind a plunger pin 41, which is slidably mounted upon a pair of rearwardly extending flanges 42, carried by the bracket 36. The plunger pin 41 has a cylindrical head 42' which projects from the side of the handle 9, and the plunger pin 41 is urged outward by a coil spring, as shown in my prior patent.

The trigger flange 38 has a shoulder 43, which may be caught behind the pin 41 when the button 42' and trigger 18 are simultaneously pressed. This latches the trigger 18 in such a position that the valve 16 is partially opened, thus permitting the air to leak past the valve to effect a cooling of the gun, as described in my prior patent.

All of the details of the metal spray gun so far described may be substantially as described in my prior Patent No. 2,058,653, the description of which is hereby incorporated by reference thereto, although I desire it to be understood that the features of the invention may also be used in guns of differing construction and different appearance.

The closure plate 23 of the gun body 12 preferably supports a thermostatically actuated switch mechanism, indicated in its entirety by the numeral 44, shown in detail in Figs. 2, 3 and 4. This switch mechanism preferably comprises a metal supporting plate 45 (Fig. 4), having a flat body 46 and a pair of right angle flanges 47, 48 engaging the plate 23. Plate 46 may be se-

cured to plate 23 by a plurality of screw bolts 49 which pass through the body 46 and are threaded into the plate 23.

The plate 46 is provided with a centrally located enlarged bore 50 for passing freely a plunger 51, which is actuated by means of a thermostat 52.

The thermostat 52 preferably comprises a bimetallic thermostat of the dished type, that is, a metal member which is provided by joining together the two dished plates 53, 54, which may be of disc shape. The metal plate 54 has a greater coefficient of thermal expansion than the metal plate 53, and when the thermostat 52 is heated the plate 54 expands more than the plate 53, and tends to reverse the curvature of the thermostat 52, as shown in Fig. 3. This tendency of the thermostat 52 is resisted by the dished formation of the disc; and consequently, there is a critical point at which the thermostat changes its curvature, to actuate the switch plunger 51.

The thermostat 52 is provided with a centrally located aperture, within which the end of the plunger 51 is secured, as shown. The thermostat 52 is supported at its edges by having its edges located in the grooves 55 of a plurality of metal posts 56, four in number, which are located at equally spaced points about the periphery of the disc thermostat 52. The metal posts 56 are secured in the plate body 46 by means of reduced cylindrical portions which are riveted over at 57.

The plate body 46 also supports a plurality of contact members 58, 59, 60, and 61, which are insulated from the plate by a sheet 62 of insulation, preferably mica, so that it will be able to withstand the temperatures. The contacts 59 and 60 are connected to the terminal posts 63, 64. One lead 65 from the terminal post 63 may be connected to one terminal of the heating element 22. The other terminal of the heating element 22 may be connected to the outgoing conductor cable 66. The other lead 67 from the contact 60 may be connected to the outgoing conductor cable 66.

The two contacts 58 and 61 may be supported upon the metal posts 68, 69, all of which are insulated from the plate 46, and the posts 68, 69 are joined by a conductor 70, in the present case. Thus the contacts 58—61 are in series with the heating element 22, and may be energized from the line cable 66 when the contacts 58 and 59 are bridged and the contacts 60 and 61 are simultaneously bridged.

The thermostat plunger 51 has its lower end (Fig. 3) adjustably connected by means of the threaded portion 71 and the nuts 72 to a metal plate 73. The metal plate 73 (Fig. 4) supports a pair of bridging contacts, comprising the metal discs 74, 75. These contacts are each loosely and substantially universally mounted on a metal plate 73 by the following arrangement:

A metal supporting stud or rivet 76 is provided with a collar 77, having a partially spherical surface 78. The collar 77 and stud 76 are riveted on the plate 73, suitable insulating washers being disposed between the collar and the washers and the stud 76 being spaced from the aperture in the plate 73. The riveted end 79 of the stud forms a head below which is mounted the bridging contact 74 in the form of a disc. The contacts 58 and 59 are spaced sufficiently so that they are not engaged by the rivet head 79, but they are engaged by the disc 74. The disc 74, being loosely mounted below the head 79 on the partially spherical surface 78, the disc 74 has a

limited universal movement and is adapted to find the proper position, engaging both the contacts 58 and 59.

The thermostat plunger 51 is thus adapted to move both the contacts 74, 75 down simultaneously and open the circuit at two places when the thermostat is heated to a predetermined degree. The point at which the thermostat opens is critical, and it may be so arranged as to keep the gun at a temperature of 560 to 600 degrees F. at the metal well 25 when the gun is under thermostatic control. In the event the plunger 51 tilts slightly, it will nevertheless open one of the contacts 74 or 75, although the other one may be closed, and thus the opening of the circuit by the thermostat is assured, irrespective of the fact that the thermostat plunger 51 may be slightly tilted when the thermostatic switch is in open position. The thermostatic switch is preferably enclosed in a cup-shaped housing 80, which surrounds the switch structure and the leads and is provided with an attaching flange 81 secured to the plate 23 by a plurality of screw bolts.

The present metal spray gun is also provided with means for rendering the thermostat ineffective whenever the gun is under operation. This means comprises the cooling effect of air which is conducted to the thermostat whenever there is a back pressure in the air tube 19. For this purpose the body 11 of the gun may be provided with a backwardly extending bore 82 for receiving a backwardly turned end of an air tube 83.

The air tube 83 extends along, under the body 11, and under the porcelain support 21 for the heating element 22, and terminates in a downwardly extending nozzle 84, which extends through an aperture 85 in the plate 23, into the chamber 86 of the thermostatic switch housing 80.

Referring to Fig. 3, it will be noted that the nozzle 84 is directed toward the thermostat 52.

The operation of the metal spray gun is as follows: The electric heating element 22 is energized by connecting the plug, which is at the end of the cable 66, to a standard 110 volt A. C. or D. C. lighting circuit. The thermostatic switch is normally closed, as shown in Fig. 4, and therefore the current may pass directly through the circuit, which includes the switch and heating element.

The gun is then heated up, and as soon as it reaches a predetermined temperature, the heat, which is transferred to the thermostat 52 by convection, conduction, and radiation, raises the thermostat to such a point that it reverses its curvature from that shown in Fig. 4 and opens the contacts. The gun is then at the proper operating temperature, and should it cool to a predetermined degree, the thermostatic switch will then again turn on the current, and the gun will be maintained at proper operating temperature until the operator is ready to use it.

It is advisable at this time to pull the trigger 18 and latch it by means of the plunger pin 41 so that the air under pressure, which is carried by the hose 15 to the gun, is permitted to leak past the valve 16 into the tube 19 through the gun. This effects a cooling of the interior of the gun and prevents damage to those parts of the gun which might otherwise become too hot, because there is no opportunity for radiation from the parts in the interior of the gun.

The leakage of air past the valve 16, however, does not produce any back pressure in the air tube 19, and little or no air is conducted at this

time by the tube 83 to the thermostat 52. When the operator uses the gun, however, he pulls the trigger 18 back fully, to provide a full supply of air under pressure, and a back pressure is created in the pipe 19. Then air is conducted by the pipe 83 to the thermostat 52, and in a very short time the thermostat is so cooled that if the switch is not already closed, it is closed then by the thermostat. Thus the air which is conducted from the air supply to the thermostat serves to effect a quick closure of the thermostatic switch, thereby giving instant heat to replace that taken from the nose of the gun by the cold solder. The thermostat does not become ineffective, but it resumes control of the gun at, for example, about 750 degrees, so that the temperature of the gun never exceeds that point. When the gun is ready for operation but not being used, the thermostat is adapted to function at a temperature of approximately 600 degrees F., which is a suitable temperature for beginning operations.

The present gun employs a relatively large heating element, such as, for example, a 900 watt element, which furnishes ample heat for the gun under continuous operation. With the present thermostatic arrangement, the gun has two temperatures: one temperature at which it is maintained when ready but not operating, and another temperature at which it is maintained when actually melting solder. The air supply is utilized to change the characteristics of the thermostat with respect to the body of the metal spray gun.

Thus, while the gun is maintained under thermostatic control, it is kept at a higher temperature when it is actually operating and melting solder. There is no possibility that the present gun will be damaged, since it is protected at all times against over-heating, by the action of the thermostatic switch.

It will thus be observed that I have invented an improved metal spray gun which is protected by a thermostatic switch, so that the gun cannot be over-heated at any time. As soon as the gun is placed under operation, the thermostatic switch and air pipe arrangement provide an instantaneous supply of additional heat, for the melting of solder. The gun temperature is boosted as soon as the gun starts operating. The gun is then maintained at proper operating temperature for melting solder; but as soon as the gun is not actually in use, the air supply to the thermostat is cut out, and the thermostat functions at a normal temperature of approximately 600 degrees F.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. In a metal spray gun, the combination of a metal body provided with a metal well, an air nozzle carried by said body, a source of heat for said body comprising an electric heating element, thermostatic means for controlling said heating element, and means tending to cool said thermostatic means when the gun is operated, said thermostatic means being effective at one temperature during the operation of the metal spray gun, and at another temperature when the gun is hot but not operating.
2. In a metal spray gun, the combination of a

metal body provided with a metal well, an air nozzle carried by said body, a source of heat for said body comprising an electric heating element, and thermostatic means for controlling said heating element, said thermostatic means being effective at one temperature during the operation of the metal spray gun, and at another temperature when the gun is hot but not operating, said thermostatic means comprising a dished bi-metallic thermostat and an electric switch actuated by said thermostat, and an air conduit connected to the air nozzle of said gun for conducting cooling air into the vicinity of said thermostat whereby the thermostat is subjected to cooling air when the gun is under operation.

3. In a metal spray gun, the combination of a metal body provided with an electric heating element and having a metal well and an air nozzle, a thermostatic switch connected in circuit with said electric heating element and adapted to control the energization of said heating element, said thermostatic switch being connected to said metal body to receive heat from said metal body by radiation and conduction and means for changing the operation of said thermostatic switch when the air pressure is created in said air nozzle during the operation of the gun, said means comprising an air conduit in communication with said air nozzle and adapted to be provided with a supply of air due to back pressure in said nozzle, said air conduit conducting cooling air to the thermostat of said switch.

4. In a metal spray gun, the combination of a metal body provided with an electric heating element and having a metal well and an air nozzle, a thermostatic switch connected in circuit with said electric heating element and adapted to control the energization of said heating element, said thermostatic switch being connected to said metal body to receive heat from said metal body by radiation and conduction, and means for effecting a temperature change in said thermostatic switch so that the switch is promptly closed when the air pressure is created in said air nozzle during the operation of the gun said latter means comprising an air conduit discharging air upon the thermostat, said spray gun being provided with an air control valve, and means for manually controlling the actuation of said air control valve.

5. In a metal spray gun, the combination of an electric heating element with a metal spray gun, thermostatic switch means carried by said spray gun for controlling the energization of said electric heating element, and means for affecting the operation of said thermostatic switch means comprising a supply of cooling air under pressure directed on the thermostat whereby the circuit to the heating element will be broken only at a higher predetermined temperature when the metal spray gun is in operation.

6. In a metal spray gun, the combination of a metal body provided with a well comprising a downwardly tapered bore having a nozzle opening for receiving metal and discharging it after it is melted, said body housing an electric heating element, a second metal body for supporting

the first-mentioned metal body, said second body having a plurality of points of attachment, and having the major portion of its adjacent surface out of contact with the first-mentioned body, a handle for supporting said second body, and means for securing said handle to the second body, comprising a plurality of posts and spaced plates carried by said posts for radiating heat, an air tube carried by said bodies, said air tube having one end communicating with a fitting adapted to be attached to a source of air under pressure, and having the other end formed with an arcuate nozzle aperture, said arcuate nozzle aperture being arranged to discharge air in the form of a trough beneath the point of discharge of melted metal from said well, and thermostatic means comprising a thermostat, and an electric switch actuated thereby, said switch being connected in series with said electric heating element for cutting off the electric current at a predetermined temperature, whereby the overheating of the metal well and the burning of the metal to be melted is prevented, and manual means for controlling the operation of said thermostat and rendering the thermostat ineffective to open the switch in circuit with the electric heating element except at a predetermined higher temperature when the gun is operating.

7. In a metal spray gun, the combination of a metal body provided with a well comprising a downwardly tapered bore having a nozzle opening for receiving metal and discharging it after it is melted, said body housing an electric heating element, a second metal body for supporting the first-mentioned metal body, said second body having a plurality of points of attachment, and having the major portion of its adjacent surface out of contact with the first-mentioned body, a handle for supporting said second body, and means for securing said handle to the second body, comprising a plurality of posts and spaced plates carried by said posts for radiating heat, an air tube carried by said bodies, said air tube having one end communicating with a fitting adapted to be attached to a source of air under pressure, and having the other end formed with an arcuate nozzle aperture, said arcuate nozzle aperture being arranged to discharge air in the form of a trough beneath the point of discharge of melted metal from said well, and thermostatic means comprising a thermostat, and an electric switch actuated thereby, said switch being connected in series with said electric heating element for cutting off the electric current at a predetermined temperature, whereby the overheating of the metal well and the burning of the metal to be melted is prevented, and manual means for controlling the operation of said thermostat and rendering the thermostat ineffective to open the switch in circuit with the electric heating element except at a predetermined higher temperature when the gun is operating, said manual means including a trigger-operated air valve interposed in the air pressure line to the air tube, and said gun including means communicating with the air tube for blowing air on said thermostat when said valve is opened.

FRANS O. ALBERTSON.
